UNITED STATES PATENT OFFICE

JOHN C. MARSELLUS, OF SYRACUSE, NEW YORK

DESIGN FOR A BURIAL CASKET

Application filed November 15, 1930. Serial No. 37,664. Term of patent 14 years.

To all whom it may concern:

Be it known that I, JOHN C. MARSELLUS, a citizen of the United States, residing in the city of Syracuse, county of Onondaga, and State of New York, have invented a new, original, and ornamental Design for Burial Casket, of which the following is a specification, reference being had to the accompanying drawings, forming part thereof.

Figure 1 is a perspective view of a burial casket showing my new design in which the corners —a— of the bottom moulding —A— and the corners —b— of the top moulding —B— of the casket body are square while the corners —1— of the portion of the casket

body between the mouldings —A— and —B— are quarter round and are provided with rounded fillets —2— at their junctions with the square corners of the mouldings.

Figure 2 is an enlarged horizontal sectional view through one of the corners of the box body taken in the plane of line 2—2, Figure 1.

Figure 3 is a diagonal sectional view through one of the corners taken in the plane of line 3—3, Figure 2.

I claim:

The ornamental design for a burial casket substantially as shown and described.

JOHN C. MARSELLUS.
